Primary Examiner — Darlington Ly

(57) **CLAIM**

The ornamental design for a folding drone, as shown and described.

DESCRIPTION

1.1 is a top and side perspective view of the folding drone showing our new design, wherein the wings are shown in a folded position;

1.2 is a top plan view of the folding drone, wherein the wings are shown in a folded position;

1.3 is a top and side perspective view of the folding drone, wherein the wings are shown in an unfolded position;

1.4 is a bottom and side perspective view of the folding drone, wherein the wings are shown in an unfolded position;

1.5 is a top plan view of the folding drone, wherein the wings are shown in an unfolded position;

1.6 is a front elevation view of the folding drone, wherein the wings are shown in an unfolded position; and,

1.7 is a side elevation view of the folding drone, wherein the wings are shown in an unfolded position.

1 Claim, 7 Drawing Sheets
